CONTAINER AND CLOSURE THEREFOR

Herbert Rubin, New York, N. Y.

Application January 11, 1947, Serial No. 721,518

7 Claims. (Cl. 215—43)

1

This invention relates to containers for dispensing liquid or fine granular materials and closures therefor and more particularly to such containers which are easily assembled and easily manipulable and can readily be ornamented.

While considerable effort has been expended in the cosmetics and toiletries fields to market such products in attractive, distinctive containers, the stress on attractiveness has often minimized the utility. On the other hand, containers, and particularly the closures of the same, when made with the stress on utility, have lost their attractiveness. Thus, the container either does not make an attractive display, or else it does not work well when put to the use for which it is intended. The marketing of the commodity is accordingly affected, not by its own qualities, but by the container in which it is dispensed. When the commodity being dispensed is expensive, a more costly container can be employed and the problem is not so pressing. When, however, the cost of the container must be kept at a minimum, due to the inexpensive nature of the commodity carried in it, the problem of furnishing a fully effective and distinctive container is a real one.

Heretofore, in the inexpensive types of containers, attractive forms of paper or cardboard were used for completing them and dressing them up. The use of these calls for the performance of hand operations in applying the paper or cardboard parts to the containers, such as the gluing of strips around the neck of a bottle and other comparable operations. Considering present labor costs, however, it can be readily appreciated that the cost of such operations is prohibitive. Thus, some other approach had to be found while keeping in mind that distinctiveness is desirable while attractiveness and utility must be preserved. I believe that I have achieved those ends by means of the instant invention.

The container of my invention enables the incorporation of attractiveness and distinctiveness of appearance with a functioning which is effective and intriguing. Nevertheless my container is economical of production and assembly, quite contrary to what its appearance would indicate. The decorative scheme imparted to the embodiment selected for illustrating the invention is that of an Early American oil lamp. This appearance is an attractive one but belies the fact that the device is in reality a dispensing container with a novel and effective closure, in the functioning of which the apparent lamp elements play important parts. The container could just as readily be formed to simulate other types of lamps and could take on many other forms, entirely remote from that of a lamp.

In the container shown, an economical base, or bottle part, is closed by means of a cap type

2

closure, susceptible of being turned out economically on automatic machinery. Since this base is given the form of the base of an Early American oil lamp, the application of an apparent chimney for such a lamp is most fitting. This simulated chimney, however, is formed of a resilient plastic, with a lower end of substantially the same diameter as the outside of the closure member. This lower end, when engaged over the closure member grips the same with sufficient force to enable the simulated chimney to be used as a means for unscrewing the closure member. In addition, such lower end, or collar formation, serves to maintain a simulated oil lamp gallery in place. This apparent gallery also carries a handle to complete the simulation of an oil lamp while, at the same time, serving as a gripping means.

The simulated gallery though made of metal, can be turned out most economically on automatic machinery. It is a most simple job to secure the gallery in place at the time the lamp chimney is applied to the closure cap. In fact, assembly labor is so reduced that though the gallery is made of material substantially more expensive than paper, the labor cost for assembly is so low that the overall cost for labor and material is well below what it would be if a paper gallery were used. Furthermore, no paper gallery, though adhered to itself, or to the simulated chimney, could perform the handle supporting function of the construction of my invention.

It is accordingly an object of my invention to provide an economical dispensing container of attractive appearance.

Another object is to provide a readily operable and extremely convenient closure for such a container.

Another object of my invention is to provide such a container which can be assembled with a minimum of labor.

Still another object of my invention is to provide such a container which readily lends itself to ornamentation.

Further and more detailed objects of my invention will become apparent as the description of the illustrative embodiment of the invention, shown on the accompanying drawing, proceeds.

In that drawing—

Figure 1 is a side elevation of the container of my invention.

Figure 2 is a vertical section taken on line 2—2 of Figure 1.

Figure 3 is an exploded view of the container of my invention, showing the elements thereof separated but in the relative positions that they occupy when assembled.

Figure 4 is a top plan view of the base of my container showing a modified form of closure cap applied thereto.

Figure 5 is an elevation of the modification shown in Figure 4, and

Figure 6 is an enlarged fragmentary section of a modified form of operating element for the closure cap, shown as applied to the closure cap.

As already pointed out my invention is illustrated in the accompanying drawing as applied to a container having the appearance of an oil lamp. It is of course to be understood that the invention is applicable to simulations of a variety of oil lamps, besides the one here chosen for illustrative purposes. In addition, the invention is applicable to a further variety of containers distinct in appearance from oil lamps.

The container of my invention, generally indicated at 1, has the configuration of a rather squat fount of an oil lamp. The base of the container is indicated at 2, the body portion at 3, and the constricting upper portion at 4. Such upper portion 4 extends into an upwardly extending neck, generally indicated at 5, which neck serves to define the dispensing opening of the container.

A collar 6 extends laterally outwardly a substantial distance from the neck 5 at a position just above where the neck departs from the portion 4. The upper surface of the collar 6 furnishes a broad shoulder 7, horizontally disposed with respect to the vertical axis of the container 1. The portion 8 of the neck 5, extending upwardly from the shoulder 7, is formed with an external screw thread, in order to receive a screw threaded closure member.

The closure member to close the open upper end of the portion 8 is of the cap type. Such a member, generally shown at 9, has a top in the form of a dome 10, and a side wall 11, formed with screw threads to mate with the external screw threads on the portion 8. A gasket 12 is received within the dome 10 to overlie the open end of the portion 8 and close the same, the side wall 11 being a little short of the shoulder 7 to allow for compression of the gasket and possible variances in the dimensions of the related parts.

The closure member 9 is normally applied with a moderate hand-tight firmness, so that it can be removed by a similar action. In the normal use of my container, however, the cap shaped closure member will be actuated by means other than direct hand contact. This actuating means, as shown at 13, simulates the chimney of an oil lamp. Unlike a common oil lamp chimney, however, the simulated one of my invention is not made of non-yielding glass, but of carefully selected resilient material. Suitably, such material can be a plastic having proper cold flow characteristics as hereinafter pointed out. Thus the chimney type member is capable of being expanded radially to a reasonable degree, but will return to its normal position on removal of the expanding forces. This member has a suitably decorated open top 14, is concaved inwardly at 15 as it extends downwardly, and flares outwardly towards its lower portion in the round bellied part 16. This latter part provides a suitable hand grip by which to grasp the chimneylike member for application, or actuation, of it.

Below the portion 16 the member 13 converges into a constricted cylindrical collar portion 17. The collar portion 17 has an internal diameter normally slightly less than the external diameter of the side wall 11 of the cap like closure member. Furthermore, the height of the portion 17 is generally comparable to that of the side wall 11. As seen in Figure 3 a curve 18 is provided

on the member 9 where the top 10 and side wall 11 come together. Hence when the chimney like member 13 is grasped about its portion 16 and forced on to a cap 9, the curve 18 serves as a lead to start the expansion of the collar portion 17 and enable the same to be forced down over the side wall 11 to its final position as shown in Figure 2.

The purpose of the resilient engagement between the collar 17 and the side wall portion 11, is not merely to hold the simulated chimney in place on the closure cap. The engagement is effective far beyond that. It is of sufficient force to enable one to remove the closure member 9 by merely gripping the bellied out portion 16 of the simulated chimney and turning it. Thus the closure member is provided with an operating handle which is additionally a decorative feature of the device.

In addition to the functions already ascribed to the resilient relationship of the portions 11 and 17, the same also serves to suitably mount the handle on the container. This handle is carried by a simulated oil lamp gallery shown per se in Figure 3, as having an annular base portion 19, underlying the end of the collar portion 17. The base portion 19 supports a series of upstanding fingers 20 which extend upward from its periphery to engage the exterior of the portion 17, and serve with the base 19 to complete the simulation of an oil lamp gallery. The base 19 also supports the handle member 21, which extends out from its periphery between two of the adjacent fingers 20 into a suitable finger grip. The handle 21 may terminate at its far end, in engagement with the body of the base 19 as seen in Figure 2, though not necessarily so.

Since the portion 19 of the gallery underlies the end of the collar member 17, the gallery member will be held effectively in place when the chimney is assembled with the base. In addition the strong grip of the collar 17 on the side wall 11, assures that the handle 21 will remain firm for use in picking up the container. This will also be enhanced and any tilting tendency will be checked by the counteraction of the fingers 20 extending up the outside of the collar 17.

From the foregoing it will be apparent that the container of my invention is complete, economical, effective for the purposes intended, and in addition, is attractive in appearance. All parts, from the base, or bottle, containing the material to be dispensed, the chimney, the cap like closure member, and the gallery carrying the handle can be simply and economically machine made. The job of assembling the container is most economical, for the steps are all simple, can be performed rapidly and without any possibility of mistakes, though the labor employed be entirely unskilled. In fact, I have found that though certain parts of my construction are made more substantial than prior practices would have deemed economical, the economy in labor required in the assembly of my container far offsets the additional cost of materials, as against those used in the prior art constructions.

In Figures 4 and 5 I have shown a slight modification of the cap like closure member of my invention, to adapt the construction for use for the dispensing of powdered or fine granular material. Here the head 22 of the cap type closure member, is provided with a suitable number of suitably sized perforations 23. Thus when the base is filled with material, such as powder, salt or pepper, to be dispersed, the same can be done

through the perforations 23. Here again, of course, the simulated chimney gallery and handle are also employed, and very effectively so. In fact, the provision of an effective and attractive handle, on salt and pepper shakers, has always been a problem when the same were made of glass or porcelain. The construction of my invention provides a fully effective and economical solution to that problem. Furthermore, the chimney, due to its stack effect, is quite useful in preventing moisture laden air from working down into the container and moistening the contents thereof. This feature, in and of itself, is most desirable from the standpoint of salt alone.

In Figure 6 I have shown an enlarged section of a slightly modified form of simulated chimney. This chimney has a bellied out upper portion 24, and a lower engaging collar 25, the same as those of the simulated chimney previously described. A difference exists in the interior of the chimney's construction, however, for, instead of having a smoothly convex curve where the portions 24 and 25 merge into each other, this modified chimney has an inwardly extending shoulder 26. This shoulder results from a thickening of the material at the top end of the collar which strengthens the whole construction. Particularly this thickening reinforces, or backs up, the resilient action of the collar 25 in clamping upon the side wall 11 of the closure member 9. In addition, the shoulder 26 comes into engagement with the head 10 of the closure member and assists in maintaining the proper longitudinal relationship of these members.

It is, of course, to be understood that the particular exterior configuration of the elements of my invention, is for the purpose of enhancing the appearance thereof, and can be departed from widely without any real departure from the scope and spirit of the invention. For instance, the collar 17 or 25 might terminate in any desired type of gripping means, whether decorative or not. Also the handle support maintained in place by the collar need not be a simulated oil lamp gallery, but might be any other suitably formed support. In addition, other modifications might well occur to one skilled in the art, yet would fall within the scope of the instant invention whose only limitations should be such as are imposed on the claims which follow by the disclosures of the prior art.

Having disclosed my invention, what I claim as new and seek to obtain Letters Patent for is:

1. A container having an opening therein, surrounded by an upwardly extending neck, a cap type closure member engaged with said neck to close said opening, means to operate said closure member, said means comprising a tubular member engaging said closure member exteriorly in a friction fit, a handle member for holding said container, and means to secure said handle member in position with respect to said container, said means consisting of said tubular member and an extending portion of said handle member.

2. A device in accordance with claim 1 in which the extending portion of said handle member is an annulus overlying the end of said tubular member.

3. A device in accordance with claim 2 in which said neck is provided with a laterally extending shoulder and said handle member annulus is held against said shoulder by said tubular member.

4. A device in accordance with claim 3 in which said neck is formed with an exterior screw thread

formation above said shoulder and said closure member is provided with screw threads mating with the threads of said neck.

5. A dispensing container simulating an oil lamp, and comprising a bottle type base member, having an opening therein surrounded by an exteriorly threaded neck, and laterally extending collar adjacent the base of said neck, a cap type closure member overlying the end of said neck and secured thereto in threaded engagement with the threads of said neck, a member simulating an oil lamp chimney for operating said closure member, said last named member having a resilient portion to overlie and tightly engage said cap type closure member, a member simulating the gallery of an oil lamp having an annular portion underlying the end of said resilient portion and held in place by the same against said collar, said gallery member having fingers for overlying the exterior of said resilient portion, and also having a handle extending laterally therefrom.

6. A container having an opening therein surrounded by an upwardly extending neck, a cap type closure member engaged with said neck to close said opening, means to operate said closure member, said means comprising a tubular member engaging said closure member exteriorly in a friction fit, a handle member including a mounting portion and a hand grip portion, said mounting portion extending between and being secured in tight gripping relation between the inner end of said tubular member and the adjacent portion of said container, said tight gripping relation being the sole securing of said mounting portion, said hand grip portion extending away from said mounting portion for gripping by the hand of the user.

7. A dispensing container simulating an oil lamp, and comprising a bottle type base member, having an opening therein surrounded by an exteriorly threaded neck, and laterally extending collar adjacent the base of said neck, a cap type closure member overlying the end of said neck and secured thereto in threaded engagement with the threads of said neck, a member simulating an oil lamp chimney for operating said closure member, said last named member having a resilient portion to overlie and tightly engage said cap type closure member, a member simulating the gallery of an oil lamp having an annular portion underlying the end of said resilient portion and held in place by the same against said collar, said gallery member having fingers for overlying the exterior of said resilient portion.
